UNITED STATES PATENT OFFICE.

ARTHUR BATES, OF LEICESTER, AND HAROLD EDMUND COOPER, OF NORWICH, ENGLAND, ASSIGNEES TO UNITED SHOE MACHINERY COMPANY, OF PATERSON, NEW JERSEY, A CORPORATION OF NEW JERSEY.

SHOE-SUPPORT FOR TURN-SHOE RE-FORMING AND OTHER MACHINES.

1,121,968.

Specification of Letters Patent.

Patented Dec. 22, 1914.

Original application filed April 27, 1909, Serial No. 492,489. Divided and this application filed May 20, 1910, Serial No. 562,494. Renewed October 20, 1914. Serial No. 867,666.

To all whom it may concern:

Be it known that we, ARTHUR BATES and HAROLD E. COOPER, subjects of the King of England, residing at Leicester, in the county 5 of Leicester, England, and Norwich, in the county of Norfolk, England, respectively, have invented certain Improvements in Shoe-Supports for Turn-Shoe Re-Forming and other Machines, of which the following 10 description, in connection with the accompanying drawings, is a specification, like reference characters on the drawings indicating like parts in the several figures.

This invention relates to improvements in 15 jacks for holding boots and shoes and for stretching the uppers thereof to cause them to conform to the shape of the jack while being operated upon by any suitable finishing tool or instrumentality, or for stretching 20 and shaping the uppers without reference to any other operation.

The invention is shown and will be described in connection with the improved construction of beating and rubbing tool for 25 re-forming turn and other shoes disclosed in my co-pending application, Serial No. 492,489, filed April 27, 1909, of which the present application is a division; and while certain features of the jack herein described 30 and claimed have advantages which especially fit them for use in connection with beating and rubbing tools of the character disclosed in said prior application, and co-operative therewith in securing new and 35 valuable results in the operation of re-forming turn and other shoes, some features of the invention which will be claimed herein, are of more or less general utility in expansive jacks for stretching and shaping 40 boots and shoes.

An important feature of the invention resides in the provision of relatively movable parts to stretch the upper which are moved to expand or contract the jack by power 45 applied through clutch mechanism, that automatically stops the contraction and expansion of the jack in either of its extreme positions, to permit work to be removed from and placed upon the jack, or to be operated upon while it is being stretched.

Preferably, the jack is expanded through a yielding device in order to obviate the danger of unduly stretching the shoe while the

jack is being expanded, and a feature of the invention in this connection comprises means 55 for changing the tension of said yielding device, either before the jack is expanded or while the shoe is held in a distended condition, in order that the force acting to stretch the shoe may be increased or diminished in accordance with the size of shoe 60 being operated upon, or to lessen the expansive force of the jack for shoes of light or stretchy stock, and to increase it proportionately for shoes of heavier or less elastic stock. 65

In this connection, another feature of the invention consists in providing an adjustable stop to limit, variably, the amount of stretching movement imparted to the shoe by the movable member of the jack through 70 the yielding device before referred to, which stop acts independently of the means for adjusting the tension of such device.

Still another feature of the invention consists in providing mechanism for causing the 75 jack to expand and contract a plurality of times before coming to rest in an expanded condition. It has been found that by subjecting the shoe to a number of successive stretching movements the upper is gradually 80 brought to its final shape with less danger of injury to the stock, and in a more thorough manner, than where the jack expands once only and then comes to rest.

Other features of the invention, including important details of construction and combinations of parts, will be hereinafter 85 more particularly described and claimed.

Referring to the drawings: Figure 1 is a front elevation of the machine. Fig. 2 is 90 a left side elevation. Fig. 2^a is a detail of Fig. 2. Fig. 3 is a vertical section on the line 3—3 of Fig. 1. Fig. 4 is a front elevation, partly in section, and on a larger scale showing connections for driving the 95 beating-out device; and Fig. 5 is a detail of Fig. 4, partly in vertical section at right angles to the plane of Fig. 4. Fig. 6 is a detail showing the relative arrangement of the heel part and fore part of the jack and 100 their intermediate sole plate.

The frame 2 of the machine includes two columns 3 and 4, the former of which supports an expanding jack formed, as shown best in Fig. 2, of relatively movable arms 105 carrying the fore part and heel portion of

a shoe form. The fore part 11 is shown as supported directly by the column 3, while the heel part 13 is supported by a lever 5 which is fulcrumed at 6 to the column and 5 extends downwardly into connection with means for actuating it to move the lever from the fore part to distend lengthwise a shoe which may have been placed on the jack, a spring 17 which connects the lever 5 with the frame of the machine serving to 10 yieldingly contract the heel part to permit the shoe to be placed on the jack or removed therefrom. This arrangement provides for thrusting the heel part of the form into the 15 relatively substantial heel part of the shoe, thus drawing the forward portion of the shoe tightly about the fore part of the form or jack. The parts of the form are made removable to permit parts to be used which 20 are of appropriate size and style for different shoes to be treated.

The lower end of the lever 5 is provided with an eye in which is held a cylindrical block. The block and the eye are bored 25 transversely to receive a rod 8 which is screwed into a boss formed on a block 10 which is slotted to receive the shaft 14 so as to be capable of a limited amount of transverse movement thereon, and supports 30 a cam roll 7 which is held yieldingly in engagement with a suitable operating cam fast on the shaft 14, by the spring 17. This cam may be so shaped as to effect any desired number of contractions and expansions 35 of the jack before the machine is brought to a stop with the shoe in an expanded condition. As herein shown, the cam is designed to cause the jack to expand twice before coming to rest, and to this end it is shown 40 as having two high-points or projections 9 and 19, the latter serving to effect the final outward movement of the heel part, and being preferably of greater height than the projection 9 in order that the movements 45 imparted by the cam to the heel part may progressively increase to thereby gradually stretch the shoe. The shaft 14 is turned in bearings in the frame by a gear 15 meshing with a gear 16 having one-half the number of teeth that the gear 15 has and which 50 is driven from the main driving shaft 18 of the machine. The lever 5 is yieldingly connected with the rod 8 so that the heel part of the jack will be thrust yieldingly when it 55 is stretching the shoe by a spring 22 which encircles the rod and bears at one end against the lever 5 and at its opposite end against a hand wheel 24 threaded on the rod. The force for expanding the shoe is, therefore, 60 transmitted through this spring to the lever. The tension of this spring is controlled by the hand wheel 24 which, as shown, is located in convenient position to be manipulated by the operator at any time 65 to change the tension of the spring and

thereby the force with which the shoe is being distended; for example, this hand wheel may be manipulated while a shoe is held on the jack in distended position and by such manipulation the force acting to distend the 70 shoe may be manually increased or diminished after the automatic operation of the jack. The rod 8 also is provided with a hand wheel 25 by which it may be screwed more or less into the boss of the block 10 to 75 change the normal angular position of the lever 5 and therefore the normal relation of the lever and the fore part of the jack for shoes of different sizes. This provision renders unnecessary such frequent changes of 80 the parts of the form or jack as would otherwise be required for different sizes of shoes.

The pinion 16 or the portion of shaft carrying it is connected to the main driving shaft 18 by a clutch which may be of any 85 suitable form so arranged that when the pinion has made a predetermined number of revolutions said pinion will be automatically disconnected from the driving shaft. In the arrangement shown a one revolution 90 clutch of any suitable or ordinary construction is provided, the gearing and timing of the parts being arranged to cause the pinion to stop at the end of a complete rotation and each alternate actuation of the machine will 95 preferably cause a single rotation of the pinion to expand the jack twice and cause it to come to rest in an expanded condition. On the next actuation of the clutch the jack will be moved to contracted position to permit removal of the shoe. In Fig. 2 the machine is shown at rest with the cam roll 7 resting on the cam projection 19 in which 100 position the jack is fully expanded. Upon the next actuation of the clutch the gear 15 105 and the cam will be caused to rotate in the direction indicated by the arrow until the roll travels to lowest point 12 of the cam, when the machine will stop with the jack in contracted position. The next time the 110 clutch is actuated the cam roll will pass successively over the projections 9 and 19 which will effect two expansive movements of the jack and the machine will automatically be brought to a stop with the parts in the positions which they occupy in Fig. 2. A clutch controlling device 30 is shown in Fig. 2 arranged to be operated through a rod 32 115 depending from the hand lever 34 fulcrumed at 6 and which is normally held in the 120 position shown by a spring 35.

As has been earlier suggested, it is contemplated that the shoe which has been distended by the expanding jack to approximate substantially its normal shape and size shall be treated to smooth and shape it so that it will have the desired appearance when removed from the jack. It is found that in making shoes of very light or very stretchy stock the upper is distended too 125 130

much if the shoe is thus beaten out or otherwise treated while it remains on an expanding jack in which, as in the construction above described, the expansion is effected through a spring which continues to exert expanding force while the jack is at rest, as in Fig. 2. To prevent this difficulty in making such light or stretchy shoes the hand wheel 24, controlling the spring 22, 5 may be adjusted to relax the tension of that spring, or alternatively means may be provided for resisting the action of the spring while the shoe is held in distended condition and preventing further expansion of the 10 jack. For this purpose an eccentric 36 is shown as mounted in the column 3 in front of the lever 5 and provided with an operating lever 38 by which it may be turned into position to limit the movement of the lever 20 in the direction for expanding the jack. This eccentric may be positioned before the machine is started in the event that it is desired to use it as a stop for limiting the automatically effected expansion of the jack 25 or the eccentric may be turned down to prevent further expansion of the jack and distention of the shoe while the shoe is being treated on the expanded jack. The operating lever 38 has a spring plunger 39 for frictionally engaging a plate 40 to hold the lever in the position to which it has been adjusted. The rod 32 may have a lug 42 adapted, when the clutch controlling lever 34 is depressed, for restarting the machine 30 to contract the jack, to spring under the operating lever 38 and in the upward movement of said rod to turn the eccentric into an inoperative position. By this means the eccentric, after having been used to prevent 35 further expansion of the jack during the treatment of a shoe may be restored to its inoperative position where it will not interfere with the normal expansion of the jack with the next shoe applied to it. 40

45 The driving shaft 18 is provided with fast and loose pulleys 45, 46, the former of which has an internal gear from which is rapidly driven a small pinion on a shaft 48 connected by beveled gears 49 with a vertical shaft 50, see Figs. 1 and 3. The upper portion of the shaft 50 is tubular and telescopes a depending shaft 52 having a toothed collar 54 adapted for engagement with a recessed collar 55 on the shaft 50 50 for clutching the two shafts together. The shaft 52 is connected by a ball and socket or other suitable joint with the lower end of two telescopic sections 56, 57, of an extensible shaft, which in turn is connected, 55 as shown in Figs. 4 and 5, by a universal joint with a shaft 58 mounted in a frame 60 and connected by beveled gears with a shaft 62 upon which is fast a beating-out roll or other suitable tool 64. The frame 60 or extensions of the shaft 62 carried 60

therein are provided with handles 65 by which the roll may be lifted and moved over the work while it is being rotated through the connections described with the driving mechanism. The machine is provided with a bracket 70 conveniently arranged to receive a roll when the roll is not to be used. The bracket is so located that in placing the roll in it the extensible shaft 56, 57 is drawn out and the collar 54 is 70 lifted to withdraw its projections from the recesses in the collar 55 and thereby disconnect the shafts 50 and 52 so that the shaft 52 is not rotated by the shaft 50. When the roll is lifted from its supporting 75 bracket and brought into position for operating upon the shoe the distance between it and the frame of the machine is shortened sufficiently to allow the clutch members 54, 55 to reengage and thereby cause the roll 80 to be driven while it is in position to treat the shoe. A spring is arranged between the members 56, 57 of the extensible shaft to allow variations in the working position of the roll as it is moved over different portions of the shoe. The driving connection between the shaft 52 and the shaft 56 may conveniently comprise a ball formed in the lower end of the shaft 56 and held in the socket in the other shaft, said ball being 85 provided with a transverse bar or laterally projecting studs 72 capable of vertical movement in slots in the socket walls. This connection permits an entirely free forward and backward movement of the roll and a limited lateral movement of the roll. The driving connection between the shaft section 57 and the section 58 is similarly formed by a ball having a transverse bar 90 73 and the frame 60 has depending flanges 95 100 74. This connection permits, within certain limits, a free tipping movement of the roll in all directions. These tipping connections allow the roll to be tilted as well as moved forwardly and backwardly for rubbing or beating down different portions of the shoe to be treated. They also permit a lateral movement of the tool to bring it into position to operate upon a shoe carried by a shoe support on the second or right-hand column 105 110 115 4. It is found desirable sometimes to remove a shoe from the expansible jack after the shoe has been stretched and to apply it to a non-expansible last or support such as that shown on the right-hand column. The shoe is then beaten out by the use of the roll 64. 120

125 In the use of the machine the shoe is applied to the jack when the latter is contracted,—that is, when the cam roll rests on the low part 12 of the cam and the heel part of the jack is held by the spring 17 closely adjacent to the fore part. At this time the gear 16 will be disconnected from the driving mechanism and the beating roll 130

64 will rest in its bracket 70, as shown in Fig. 1, with the clutch members 54, 55 disconnected. The shoe will have been turned right side out before being applied to the expansible jack and to start the machine the operator will depress the controlling lever 34, whereby the cam will be actuated to rock the lever 5 yieldingly through the spring 22 a plurality of times 5 and will come to rest with the jack in the position shown in Fig. 2 in which it holds the shoe in distended condition. The rubbing roll or beating device is then lifted from its support and while being moved 10 into operative relation to the shoe, it becomes automatically connected with its driving mechanism by the descent of the clutch member 54 into driving engagement with the clutch member 55, whereby the roll is 15 rapidly turned. The operator carrying the roll in his two hands moves it over the shoe into such positions and with such pressure as in his judgment is required for beating-out the shoe. This operation upon the shoe 20 sole reforms it or shapes it and stiffens the sole so that the sole assists substantially in maintaining the relatively flexible shoe upper in its distended or re-formed condition after the shoe has been removed from 25 the jack. To restart the machine for contracting the jack the operator again depresses the controlling lever 34 and the machine comes to rest with the heel piece 30 rocked toward the fore part of the divided last or form so that the shoe can be readily stripped off the jack without distorting its shape. The shoe may then be permitted to dry on a rack for making permanent the shape given to it on the jack. If the shoe 35 under treatment at any time is being stretched too much or too little the tension of the spring 22 will be adjusted by the hand wheel 24 and if it is desired to prevent the shoe from being distended more 40 by the tension of the spring 22 during the beating-out operation on the shoe sole, the eccentric 36 may be positioned as shown in Fig. 2^a to lock the lever 5 against further movement or the eccentric may be used 45 to move the lever in opposition to the spring 22 to contract and then re-expand the jack. The heel piece 13 of the jack is preferably provided with a sole plate 75 which extends forwardly to bridge the space between the heel piece 13 and the fore part 50 11 whereby the expanded jack presents a continuous sole portion to sustain the sole of the shoe for the operation of the beating-out device thereon. The front portion of 55 the plate 75 is thin and beveled so that there is no abrupt shoulder at its end. The plate 75 is preferably of resilient material and so positioned and secured upon the heel piece that it will in all positions of the latter hug the bottom face of the fore part. 60 65

While I have shown and described an actuating cam whose construction is such that it imparts two complete expansive movements to the jack before the jack comes to rest, it is to be understood that the invention is not limited to use with this form of cam or device for expanding the jack as it is within the contemplation of the invention to provide any suitable form of cam or clutch between the power shaft of 70 the machine and the jack which will cause the jack to expand the number of times desired in each operation of the machine. 75

Having thus described my invention, what I claim as new and desire to secure by Letters Patent of the United States is:

1. The combination with an expansible shoe jack, of power driven mechanism for expanding the jack, and automatic means for controlling the operation of the power 85 driven mechanism to cause said mechanism to expand the jack repeatedly and then come to rest with the jack in expanded condition.

2. The combination with an expansible shoe jack, of power driven mechanism for expanding the jack, said mechanism including a spring through which expanding movement is transmitted to the jack, and automatic means for controlling the operation of the power driven mechanism to 90 cause said mechanism to impart to the jack a predetermined plural number of yieldingly effected shoe distended movements and then come to rest with the jack expanded to hold the shoe yieldingly in distended condition thereon. 100

3. The combination with an expansible jack, comprising a fixed fore part and a relatively movable heel part, of a lever carrying the heel part, a cam, and a rod actuated thereby and yieldingly connected with the lever. 105

4. The combination with an expansible jack, comprising a fixed fore part and a relatively movable heel part, of a lever carrying the heel part, a cam, a rod actuated thereby, and a spring through which the movement is transmitted to the lever, together with means arranged for adjustment to vary the relation of the lever to the 110 cam. 115

5. An expansible jack comprising, in combination, a fixed fore part and a relatively movable heel part, a lever carrying the heel part, a cam, a rod extended through 120 the lever and arranged to be operated by said cam, a spring carried by the rod to transmit movement to the lever in a direction to expand the jack, means for adjusting the tension of the spring, and means 125 for effecting movement of said lever in a direction to contract the jack.

6. An expansible jack comprising, in combination, a fore part and a relatively movable heel part, automatically operating 130

means yieldingly connected with the heel part to move it to distend the shoe, and means for limiting the extent to which such distention shall be effected.

5 7. An expansible jack comprising, in combination, a fore part and a relatively movable heel part, automatically operating means yieldingly connected with the heel part to move it to distend the shoe and hold 10 the shoe under tension, and means to prevent further distention being effected through said yielding connections while the shoe is so held.

8. An expansible jack arranged to support a turn shoe with its sole faced upwardly for the beating out operation, said jack comprising, in combination, a fore part and a relatively movable heel part separated on a line located under the heel seat, said 20 heel part being provided with an extension sole plate of thin metal having a thin beveled front portion arranged to overlie the bottom face of the said fore part to bridge the space between the said two parts when 25 the jack is expanded.

9. An expansible jack arranged to support a turn shoe with its sole faced upwardly for the beating out operation, said jack comprising, in combination, a fore part and a heel part separated on a line located near the heel breast, and a resilient member having a thin beveled front portion carried by one of said parts and arranged to hug the bottom face of the other part 35 when the jack is expanded whereby the said jack in its expanded condition presents a continuous support for the sole of the shoe.

10. An expansible jack comprising, in combination, a fore part and a relatively movable heel part, power-driven means for actuating the heel part to expand the jack, and a clutch mechanism constructed and arranged to disconnect said means automatically from the source of power when the 45 jack is in its extreme positions of expansion and contraction.

11. An expansible jack comprising, in combination, a fore part and a relatively movable heel part, power-driven means for 50 actuating the heel part to expand the jack, a yielding device to contract the jack, and a clutch mechanism constructed and arranged to disconnect said means automatic-

cally from the source of power when the jack is in its extreme positions of expansion 55 and contraction.

12. An expansible jack comprising, in combination, a fore part and a relatively movable heel part, power-driven means for actuating the jack to distend a shoe, and mechanism constructed and arranged to cause a predetermined number of shoe-distending movements to be imparted to the jack and then automatically disconnect said means from the source of power. 65

13. An expansible jack comprising, in combination, a fore part and a relatively movable heel part, power-driven means for actuating the jack to distend a shoe, and mechanism including a clutch constructed 70 and arranged to cause a predetermined number of shoe-distending movements to be imparted to the jack and then automatically disconnect said means from the source of power. 75

14. An expansible jack comprising in combination a forepart and a relatively movable heel part, means for automatically moving the two parts relatively to expand the jack, and means readily accessible to the 80 operator for effecting an initial adjustment of the said forepart and heel part for shoes of different sizes without thereby affecting the length of expanding movement of the jack. 85

15. An expansible jack comprising, in combination, a fixed fore part and a relatively movable heel part, power-driven means for yieldingly expanding the jack, an adjustable stop to limit the extent of such 90 expansion, mechanism including a clutch to connect said means with a source of power, and manually operated devices for actuating said clutch constructed and arranged to restore said stop to inoperative position 95 when the jack is disconnected from its source of power.

In testimony whereof we have signed our names to this specification in the presence of two subscribing witnesses.
